ALFRED CORBETT, OF IRWIN, PENNSYLVANIA, ASSIGNOR TO WESTINGHOUSE ELECTRIC & MANUFACTURING COMPANY, A CORPORATION OF PENNSYLVANIA

SWITCH MECHANISM

Application filed September 11, 1929. Serial No. 391,733.

My invention relates to switch mechanisms and particularly to switches of the type employed as main switches on current-distributing panelboards.

5 An object of my invention is to provide a switch having a relatively high current-carrying capacity and one which may be mounted in a panelboard housing of relatively shallow depth.

10 Another object of my invention is to provide a panelboard main switch wherein the contacts are disposed in the same plane and wherein a minimum movement of the switch blades is required to open the circuit.

15 A further object of my invention is to provide a main switch having the above noted characteristics wherein the current-carrying-and-interrupting capacity is increased by reason of the provision of means for interrupting the circuit of a plurality of points and the provision of arc-quenching plates adjacent to the point of interruption.

20 A further object of my invention is to provide a main switch for panelboards having arc-quenching plates for each contact that are mounted upon a one-piece insulating block.

25 A further object of my invention is to provide a main switch for panelboards having a folding operating handle that may occupy a shallow space between the switch compartment and the front face of the panelboard housing during normal operation of the switch and may be unfolded to extend exteriorly of the housing for operation of the switch to its open and to its closed position.

30 These and other objects that will be made apparent throughout the further description of my invention are attained by means of the apparatus hereinafter described and illustrated in the accompanying drawings, wherein

Figure 1 is a top plan view of a switch unit embodying features of my invention.

35 Fig. 2 is a transverse section through a distributing panel and the switch shown in Fig. 1, taken on the broken line II-II thereof.

40 Fig. 3 is a perspective view of an insulating block which constitutes a mounting for

the arc-quenching plates shown in Figs. 1 and 2, and

Fig. 4 is a top plan view of the operating handle shown in Fig. 2.

Referring to the drawings, the apparatus includes a sheet-metal housing 5 having an opening 6 to be closed by a door 7 that is hinged at 8 to a trim plate 9. The trim plate 9 is provided with inwardly directed flanges 12 that extend into engagement with a switch cover plate 13 which serves to divide the housing into a switch compartment 14 and a compartment 15 for the operating handle of the main switch to be hereinafter described.

The main switch comprises a metal base 16 that is attached to the bottom or rear wall of the housing 5 by means of bolts 17, the base plate 16 serving to support the insulating switch contact blocks 18 upon which the stationary contact jaws 19 and 21 are mounted.

The blocks 18 are spaced equidistantly about a central point on the base that is coincident with the axis of the switch shaft 22 which is pivotally mounted in a socket 23 secured to the base plate 16. The switch shaft 22 is provided with an insulating plate 24 upon which the switch arms 25 are mounted and which are disposed radially 90° apart, as indicated in Fig. 1. Each switch arm 25 comprises two blades 26 and 27 that are spaced apart at their free ends and are disposed in superimposed relation, as indicated in Fig. 2, the blades being so positioned that they are in the planes of the spaces between the contact jaws 19 and 21, respectively, and constitute a double blade for electrically connecting the contact jaws 19 and 21 when in operative engagement with the jaws. The open position of the switch arms 25 is indicated by dotted lines in Fig. 1, and the arms are shown in their closed positions by the full lines.

The switch shaft 22 is actuated through the medium of a plate 28 that is fixed to the shaft and carries a crank pin 29 to which is pivotally connected a guide bar 31 that is supported by a web 32 carried by the diaphragm 13 and having an opening 33 through which the end of the guide bar 31 recipro-

cates. A spring 34 serves to move the plate 28 to its open and to its closed position with a snap action when the end of the spring 34 has been moved over center.

5 The plate 28 is provided with an arcuate slot 35 for receiving a pin 36 carried by a saucer-like disc 37 in which the operating handle 38 is secured. The disc 37 is rotatably mounted upon the outer end of the shaft 22 which extends exteriorly of the diaphragm 13. There is thus provided a lost-motion connection between the operating handle and the switch shaft 22, the arrangement being such that, when the operating handle is moved to either its open or its closed position, a predetermined distance, the spring 34 causes the switch to move to open or to closed position with a snap action.

20 Since the specific switch-operating mechanism forms no part of my invention, it is unnecessary to more particularly describe it here.

In order to provide an operating handle that shall be readily accessible when the door 25 7 is open and which may be operated from a point exteriorly of the housing, I have provided a hinged extension 39 that is of U-shape and is pivotally connected to the handle by a hinge bolt 41. In order to operate the 30 switch, the hinge portion of the handle is moved to the broken-line position shown in Fig. 2. After the switch is operated, the portion 39 may be folded to the full-line position shown in Fig. 2 wherein closure of the 35 door 7 is permitted, as indicated in that figure.

By reason of the above described arrangement of the stationary contact jaws and the switch blades, a full opening movement of 40 the switch may be made by moving the blades through an angle of 45°, and the space required for the switch is reduced to a minimum.

In order to interrupt the circuit without 45 drawing a destructive arc, I have provided arc-quenching plates for each contact jaw that operate together in a manner similar to the arc-quenching plates disclosed in the co-pending application of Oliver S. Jennings, 50 Serial No. 606,565, filed Dec. 13, 1922 and assigned to the Westinghouse Electric & Manufacturing Company.

Each quenching-plate unit comprises an insulating block 42 having a base flange 43 by means of which the block is attached to the base plate 16 by means of the screws 44. The block 42 is provided with an integral insulating barrier 45 that extends normal to the plane of the block 42 and is provided with grooves 46 on opposite sides thereof that merge into corresponding grooves 47 in the block 42, the grooves being adapted to receive the adjacent edges of the barrier plates 48 that are preferably made of iron. The plates 48 are retained in operative position on the block

42 by means of screws 49 that extend through the perforations in the corners of the plates, as indicated in Figs. 1 and 3, the plates being indicated by dot-and-dash lines in Fig. 3.

The plates 48 are provided with slots 51 that extend inwardly from the free ends thereof, as indicated in Fig. 2, and are registered with the spaces between the contact jaws and so positioned that the switch blades 26 and 27 pass through them when the blades are moved to open position.

The ends of the switch jaws are pointed to cause final disengagement of the blades therefrom at a point adjacent to the base of the slots in order that the arc incident to separation of the blades from the contact jaws may be drawn at that point. The plates serve to cool the arc as it is drawn into the slots and readily extinguish it in the manner described in the above-referred copending application.

It has been found that, in the use of arc-quenching plates in combination with a double-break switch blade increases the interrupting capacity of the switch above that of a single-break switch blade and, consequently, currents of relatively large value may be interrupted by a switch having relatively small dimensions. This form of construction is particularly well adapted for a switch where-in conditions and the space limitations necessitate a large-capacity switch within limited confines.

While I have illustrated but one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. A mounting for arc-quenching barrier plates comprising an insulating base having a central partition disposed substantially normal to the base, the base and the partition being provided with spaced slots on opposite sides of the partition for receiving two adjacent edges of the barrier plates.

2. A mounting for arc-quenching barrier plates comprising an insulating base having a central partition disposed substantially normal to the base, the base and the partition being provided with spaced slots on opposite sides of the partition for receiving two adjacent edges of the barrier plates and a bolt extending through the base and the slots therein and passing through openings in the corners of the plates for securing the plates to the base.

3. A mounting for arc-quenching barrier plates comprising an insulating base having a central partition disposed substantially normal to the base, the base and the partition being provided with spaced slots on opposite sides of the partition for receiving two ad-

jacent edges of the barrier plates, the said base having means on one end for attaching it to a support.

4. A switch comprising a housing having an opening in the front face thereof, a door for closing the opening, a rotary switch within the housing, a partition covering the switch and spaced from the front face of the housing, an operating shaft extending through the partition, and an operating handle for the switch having a hinged folding portion that may swing exteriorly of the housing through the opening for rendering it accessible for operation and which may be folded inwardly into the space between the said front face and the partition for permitting closure of the door.

5. A switch comprising a housing having an opening in the front face thereof, a door for closing the opening, a rotary switch within the housing, a partition covering the switch and spaced from the front face of the housing, an operating shaft extending through the partition substantially normal thereto, and an operating handle for the switch having a hinged folding portion that may swing exteriorly of the housing through the opening for rendering it accessible for operation and may be folded inwardly into the space between the said front face and the partition for permitting closure of the door.

In testimony whereof, I have hereunto subscribed my name this 29th day of August, 1929.

ALFRED CORBETT.
